UNITED STATES PATENT OFFICE.

WILLIAM C. WIEDERSEIM, OF PHILADELPHIA, PENNSYLVANIA.

BOTTLE-SEALING DEVICE.

SPECIFICATION forming part of Letters Patent No. 732,481, dated June 30, 1903.

Application filed February 28, 1902. Serial No. 96,090. (No model.)

To all whom it may concern:

Be it known that I, WILLIAM C. WIEDERSEIM, a citizen of the United States, residing in the city and county of Philadelphia, State 5 of Pennsylvania, have invented a new and useful Improvement in Bottle-Sealing Devices, of which the following is a specification.

My invention relates to a novel bottle-sealing device; and it consists of a cap secured to 10 the bottle and a compressible gasket situated between the said cap and the inner wall of the neck of the bottle.

It further consists of other novel features of construction, all as will be hereinafter set 15 forth.

Figures 1, 2, 3, 4, and 5 represent sectional views of a bottle-sealing device embodying my invention.

Similar letters of reference indicate corresponding parts in the figures.

Referring to the drawings, A designates the neck and mouth of a bottle which is provided with an exterior shoulder B.

C designates a sealing-cap having a flange 25 D, which is adapted to engage with said shoulder B by being bent or otherwise caused to contact therewith, whereby the cap is firmly held in position, a suitable portion E of said flange projecting somewhat, affording a surface 30 face to be engaged by a suitable device for removing the cap.

F designates a shoulder on the cap which may be formed by the proper bending of the cap, which shoulder is adapted to enter the 35 mouth or neck of the said bottle and forms a seat or support for a compressible gasket G, which when the cap C is in position is seated between the said shoulder F and the inner wall of the mouth or neck of the bottle at the 40 outer end thereof, it being seen that the said gasket will be forced by the compression between the mouth of said bottle and the sealing-cap and will thus fill any inequalities there- 45 in which occur in bottles no matter how carefully made, and the gasket will thus form a tight joint or seal and at the same time act as a cushion for said cap at this point, the ob- 50 jection of which is evident. It will be seen that in this manner I form a holder or sup- port for the gasket, and I may in some in- stances form the shoulder inclined, as at H,

whereby the cap is adapted to fit bottles with various-sized mouths, as will be evident, and I may also form a protector for the gasket by bending the cap to form an edge J or secure 55 a plate K of suitable material thereto, whereby the material forming the gasket may be used without danger of injuring the contents of the bottle.

It will be seen that the flange D of the cap 60 may fit the wall of the lip of the bottle or not, as desired, but that in either instance I have provided a complete seal for the bottle, which is effective in practice, economical in construction, and one that can be easily and 65 quickly applied and removed, the removal of the cap being effected by engaging the projection E with a suitable implement, it being evident that the said projection being either at the lower edge of the flange or at a point 70 therein between the top and the lower edge or projecting inwardly at the shoulder F.

It will be apparent that slight changes may be made by those skilled in the art which will come within the scope of my invention, and 75 I do not, therefore, desire to be limited in every instance to the exact construction I have herein shown and described.

Having thus described my invention, what I claim as new, and desire to secure by Letters 80 Patent, is—

1. The combination with a bottle and a sealing-cap having means for securing the same to the bottle, of a compressible gasket situated within the mouth of the bottle and adapted 85 to be compressed between the cap and the said mouth whereby any inequalities in the said mouth will be filled and a tight joint result.

2. The combination with a bottle and a sealing-cap having a portion thereof adapted to enter the mouth of the bottle and having means for securing the same to the bottle, of a gasket suitably held in said cap and pressed to flow around or into any inequalities in the 95 mouth of the bottle.

3. The combination with a bottle having an exterior shoulder, of a sealing-cap, having a portion thereof adapted to enter the mouth of the bottle, a compressible gasket between 100 said portion and the inner wall of the said mouth, a flange on said cap adapted to en-

gage with said shoulder, and a projecting portion on said flange to afford a surface to be engaged for removing said cap.

4. The combination with a bottle having an exterior shoulder, of a sealing-cap, having a flange which is bent into contact with said shoulder, a shoulder on said cap adapted to enter the neck of the bottle and the walls of which are inclined, and a compressible gasket situated between the shoulder of the cap and the inner wall of the neck of the bottle.
5. The combination with a bottle having an

exterior shoulder, of a sealing-cap, having a flange which engages with said shoulder, a compressible gasket which is situated between the said cap and the inner wall of the neck of the bottle, and a protector below said gasket whereby the same is prevented from coming in contact with the contents of the said bottle. 15
